INVENTOR

UNITED STATES PATENT OFFICE.

JAMES W. CATTY, OF NEW YORK, N. Y.

DESIGN FOR A DOILY.

SPECIFICATION forming part of Design No. 32,605, dated April 24, 1900.

Application filed January 27, 1900. Serial No. 2,965. Term of patent 7 years.

To all whom it may concern:
Be it known that I, JAMES WALTER CATTY, a subject of Her Majesty the Queen of Great Britain, residing in New York, borough of Brooklyn, in the State of New York, have invented and produced a new and original Design for a Doily or Similar Article, of which the following is a specification, reference being had to the accompanying drawing, forming part thereof.

The figure is a plan view of a square piece of paper or cardboard, showing my new design of a doily or similar article.

As shown in the drawing, the leading or material feature of my design consists of a line of perforated dots A a short distance from each side of the edge of a square of paper or cardboard, each line equally distant from the edge of the paper or cardboard and intersecting each other near the four corners. Inside these is a series of two lines of diamond-shaped perforations B in form of a small

square, with filigree work C at each corner. Again, inside this is a small but wider square of perforations D, consisting of circles surrounded and filled in with intersecting fine lines. Inside this is a still smaller square E of the same design as B, each corner having similar design to C. The center of the paper is left blank, as shown at F. The whole is cut out of paper or cardboard in one piece.

Having described my invention, what I claim as new, and desire to secure by Letters Patent, is—

The design for a doily or similar article as herein shown and described.

In testimony whereof I have signed my name to this specification in the presence of two subscribing witnesses.

J. W. CATTY.
